UNITED STATES PATENT OFFICE.

WILLIAM A. McCOLLOUGH, OF WEBSTER CITY, IOWA.

HOG FEEDER.

Application filed March 17, 1927. Serial No. 176,069.

The primary object of this invention is to provide an improved construction for a feeding device for automatically supplying feed to domestic animals, particularly hogs.

5 A further object of this invention is to provide a feeding device having a plurality of feeding doors which may be separately lifted by the animals for feeding purposes and which may be lifted conjunctively by manual 10 operation and held in raised position at times for the purpose of cleaning the feed trough.

A further object is to provide improved means for hinging the doors to the frame.

15 Still another object of the invention is to provide improved rotary agitating devices for causing the feed to be discharged from the hopper to the troughs.

A further object is to provide an improved 20 removable metallic liner for the troughs.

More specifically, a further object of the invention is to provide a device of the class described which is of economical and substantial construction, having its base portion 25 composed principally of wood and the superposed hopper composed principally of sheet metal and so arranged as to provide a watershed at the base of the hopper and discharging 30 upon inclined doors which normally close the feeding troughs.

With these and other objects in view my invention consists in the construction, arrangement and combination of elements hereinafter set forth, pointed out in the 35 claims and indicated by the accompanying drawing in which—

Fig. 1 is a perspective view of the complete device showing one of the feeding doors in open position and portions of other doors 40 broken away.

Fig. 2 is a cross-section on an enlarged scale on the line 2—2 of Fig. 1 and showing the doors on one side held in open position as for cleaning purposes.

45 Fig. 3 is a horizontal section on an enlarged scale on the line 3—3 of Fig. 1, showing a portion of the device.

Fig. 4 is a perspective view of one of the feeding doors detached.

50 Fig. 5 is a perspective view of one of the rotary agitators detached.

Fig. 6 is a perspective view of one form of hinge clip.

55 Fig. 7 is a perspective view of a modified form of hinge clip which may be employed.

The feeder is composed in a general way

of a base portion which is formed principally of wood and a bin or hopper composed principally of sheet metal, superposed on the base, and in this instance the base is provided 60 with feeding troughs on both sides of the hopper. In the construction of the device as shown, I employ spaced base bars 10, 11 and 12, in this instance three in number, which are designed to rest on a floor or on 65 the surface of the ground. Three sills 13, 14 and 15 are arranged on and fixed to the cross-bars 10, 11 and 12, the central sill 13 being arranged on edge while the side sills 14 and 15 lie flat on the opposite end portions of the bars. Side boards 16 and 17 are mounted on and fixed to the cross-bars just outside of the sills 14 and 15. The boards 16 and 17 are rather narrow and form the sides of the feeding troughs. Floor 70 boards 18 and 19 are fixed at their inner ends on the central sill 13 and slope downwardly and outwardly to the side boards 16 and 17 respectively and rest on and are fastened to the outer sills 14 and 15. Suitable 75 end members 20 and 21 are provided for the base, which members are fixed to the ends of the boards 16 and 17 outside of the end cross-bars 10 and 12, and said end members project above the said side boards and are 80 narrower at their tops than the space between such boards. Extending longitudinally of the device and fixed at their ends to the tops of the end members 20 and 21 are 85 spaced rails 22 and 23, which rails have outwardly inclined upper faces. The bin or hopper is fixed to and rises from the end members 20 and 21 and rails 22 and 23 and is composed of sheet metal side walls 24 and 25 and end walls 26. A suitable cover 27 is 90 provided for normally closing the top of the hopper, the bottom of the hopper being open and discharging to the base portion and the troughs thereof. The lower margins of the side walls 24 and 25 are turned outwardly 95 across the tops of the rails 22 and 23 and project beyond the outer faces of said rails to provide inclined water-sheds 28 and 29.

Hinge rods 30 and 31 are mounted along side the outer faces of the respective rails 22 and 23, near the lower edges thereof and a series of feeding doors 32 and 33 are pivotally attached to said rods. The doors 32 and 33 are formed of heavy sheet metal and project at their outer margins materially beyond the side boards 16 and 17 of the base. Each door preferably is formed with an up-

turned flange 34 at its outer margin and with upturned flanges 35 at its side margins, which flanges are cut away on inclined lines at their ends. This provides for discharge 5 of the water which is conveyed upon the doors from the water-sheds 28 and 29. At its upper margin, each door 32 and 33 is formed with a curved flange 36, formed on an arc of approximately 180 degrees and 10 opening downwardly, said flange partially embracing one of the hinge rods 30 or 31. When the doors are in closed position their side flanges 35 are substantially in contact successively, but the hinge flanges 36 stop 15 short of the side margins of each door as clearly shown in Fig. 4. Hinge clips are mounted on the outer faces of the rails 22 and 23, one at each end and one between each pair of successive doors of a series. 20 The preferred form of clip, shown in Fig. 6, comprises a body 37 formed with holes 38 by means of which it may be attached to one of the rails by means of lag screws 39. At its lower end, each clip is turned outwardly 25 from the rail and then extends on an arc around a pivot rod 30 or 31, providing an arcuate bearing portion 40 which terminates against the outer face of the rail. Between its ends the bearing portion 40 is reduced in 30 width to form a shoulder 41 on each side. The reduced portions of the bearings 40 are arranged between successive hinge flanges 36 of adjacent doors while the wider portions including the shoulders 41 overlie said 35 curved hinge flange and prevent removal of the doors from the hinge rods. In the form of clip shown in Fig. 7 the body 37 extends downwardly and thence outwardly in a curved bearing portion 40' of approximately 40 360 degrees circumference, which terminates against the outer face of the body of the clip. In this instance the intermediate portion of the bearing 40' is of less width than the body 45 of the clip and of less width than its own terminal portion thereby providing its shoulders 41' which have the same function as just described.

Lifting bars 42 and 43 are arranged lengthwise of each side of the base or trough. 50 The lifting bars are of angular form and normally they embrace and rest upon the inner upper corners of the side boards 16 and 17 respectively and just beneath the respective series of doors 32 and 33. At each 55 end, the lifting bars 42 and 43 are provided with metal straps 44 attached thereto and extending inwardly along the inner faces of the end members 20 and 21, to which they are pivotally attached by means of lag 60 screws 46 or the like. Either of the doors of a series may be lifted separately by an animal desiring to feed from the device by inserting his nose beneath the projecting edge of the door, and when the animal withdraws from feeding position the door so 65

lifted will fall by gravity to its normal position upon the edge of the trough as shown at the left of Fig. 2. This arrangement serves to protect the contents of the trough from the entrance of dirt or other foreign substances as well as rain or snow and yet permits easy access for feeding purposes. It also prevents an animal from getting into the trough, as he will ordinarily be able to open only one door at a time, and these doors 70 divide the troughs into feeding spaces because each door is made a proper width for the ordinary feeding space. When it is desired to clean the trough or to gain access thereto for other purposes, the bars 42 or 43, 75 or both, may be lifted manually, thus conjunctively raising all the doors of the series as indicated at the right in Fig. 2. The series of doors may be held in this position by engagement of an annular clip 47 fixed 80 midway of the under surface of one of the doors of each series and adapted to engage the outer edge of a lifting bar 42 or 43 when said bar has been raised through a certain 85 arc.

It may be desirable at times to provide agitating devices in the base portion of the device beneath the hopper and I have illustrated such an arrangement in Figures 2, 3 and 5. Each agitating device is in this instance, formed of several bars or straps of metal secured together and arranged so as to provide six radiating arms. As here shown, two bars 48 and 49 are arranged end to end and slightly spaced apart, while substantially U-shaped arms 50 and 51 are mounted on opposite sides of the straight bars 48 and 49 and rigidly secured thereto. The space between the arms may be reamed out to form a central bearing 52 through 100 which a lag screw 53 may be mounted and fitted in the floor of the trough, whereby the agitator is mounted for rotation in a substantially horizontal plane. As many of these agitators may be provided for a trough 105 as are deemed necessary and their function is to agitate and cause feed in the hopper or piled up above the trough to be moved downwardly and outwardly as the animals move 110 said agitators in the act of feeding.

It may also be desirable to provide removable metallic liners for the troughs which may be replaced from time to time as wear or corrosion impairs their efficiency. Such liners are shown in Fig. 2 and each 115 comprises a body portion 54 resting on the floor boards 18 or 19 of the respective troughs and preferably extending from end to end thereof. The inner edges of the liners are inserted beneath the arms of the 120 agitators, which preferably are bent up or cut away at their ends to prevent catching on said liners. The liners are bent upwardly near their outer faces to form inclined portions 55 designed to rest against 125

the fillets 56 which customarily are mounted in the angle between the floor boards and side boards of the troughs, and thence are extended upwardly at 57 along the inner 5 faces of the side boards. At their top margins the liners preferably are turned inwardly to form horizontal flanges 58 which may be conveniently grasped to facilitate the operation of handling the liners 10 and particularly in removing them from the troughs.

I claim as my invention:

1. In a hog feeder, a base portion formed with a feeding trough, a frame member extending along the inner upper portion of said trough, a series of doors hinged at one end to said frame member and adapted normally to extend across the top and project beyond the outer wall of said trough, an 15 angle-shaped lifting bar adapted to embrace the top of the outer wall of the trough and to extend beneath all of said doors, straps fixed to said lifting bar and having a pivoted connection with the inner faces of the end 20 walls of said trough, and a clip fixed to the lower face of one of said doors and adapted 25

to engage said lifting bar at times for holding said bar and the entire series of doors in elevated position.

2. In a hog feeder, a feeding trough having a frame member extending along its inner upper portion, a hinge rod carried by said frame member, a series of clips fixed to said frame member and each having an arcuate bearing portion engaging said rod, 30 a series of doors each having a bearing flange pivotally engaging said hinge rod between successive clips, each clip being formed with a shoulder overhanging the end portion of a bearing flange of one or more of said doors 35 to prevent removal thereof from the rod.

3. In a device of the class described, a frame member, a hinge rod carried thereby, a clip fixed to said frame member and having an arcuate portion engaging said rod, 40 a portion of the bearing of each clip being reduced in width to form a shoulder, and a door having a bearing flange concavo-convex in cross-section and engaging said rod, each 45 end of said bearing flange extending beneath the shouldered portion of one of said clips. 50

WILLIAM A. McCOLLOUGH.
